Patented Oct. 8, 1974

233,117

CONDIMENT DISPENSER OR THE LIKE

James B. Swett, Barrington, R.I., assignor to Dart
Industries Inc., Los Angeles, Calif

Filed Apr. 13, 1973, Ser. No. 350,870

Term of patent 14 years

Int. Cl. D7—06

U.S. Cl. D7—52

FIG. 1

FIG. 2

FIG. 3

FIG.7

FIG. 1 is a side elevational view of a condiment dispenser or the like showing my new design;

FIG. 2 is a bottom plan view thereof;

FIG. 3 is a top plan view thereof;

FIG. 4 is an exploded side elevational view thereof;

FIG. 5 is a top plan view thereof with the cap removed and with the pump rotated to an operative position;

FIG. 6 is a partial front elevational view thereof of FIG. 5; and

FIG. 7 is a partial rear elevational view thereof of FIG. 5.

I claim:

The ornamental design for a condiment dispenser or the like, substantially as shown and described.
